DESIGN FOR A SWEATER-BLOUSE

William P. McGrail, New York, N. Y., assignor to McLoughlin Manufacturing Company, New York, N. Y., a corporation

Application April 29, 1935, Serial No. 56,612

Term of patent 7 years

To all whom it may concern:

Be it known that I, William P. McGrail, a citizen of the United States, residing at New York, in the county and State of New York, have invented a new, original, and ornamental Design for Sweater-Blouse, of which the following is a specification, reference being had to the accompanying drawing, forming part thereof, wherein

Fig. 1 is a front view of a sweater-blouse embodying my new design and Fig. 2 is a rear view of the blouse shown in Fig. 1.

I claim:

The ornamental design for a sweater-blouse substantially as shown.

WILLIAM P. McGRAIL.
